TEOFIL SOKOLOWSKI, OF ST. LOUIS, MISSOURI, ASSIGNOR OF ONE-HALF TO EDWARD F. MARITZ, OF ST. LOUIS, MISSOURI.

BALANCE-STAFF FOR WATCHES.

1,075,387.

Specification of Letters Patent.

Patented Oct. 14, 1913.

Application filed July 11, 1912. Serial No. 708,920.

To all whom it may concern:

Be it known that I, TEOFIL SOKOLOWSKI, a citizen of the United States, residing at St. Louis, in the State of Missouri, have invented certain new and useful Improvements in Balance-Staffs for Watches; and I do declare the following to be a full, clear, and exact description of the invention, such as will enable others skilled in the art to 5 which it appertains to make and use the same.

This invention relates to improvements in balance staffs for watches.

One object of the invention is to provide 15 a balance wheel staff having an improved construction of bearings whereby the balance wheel will be protected against jars caused by the watch being dropped or brought into forcible engagement with other 20 objects.

Another object is to provide an improved means for holding the jewels of the balance staff bearing in place.

With these and other objects in view, the 25 invention consists of certain novel features of construction, and the combination and arrangement of parts as will be more fully described and claimed.

In the accompanying drawings; Figure 1 30 is an enlarged sectional view through a portion of the balance wheel supporting plates of a watch showing the construction and arrangement of my improved staff and jewel holding mechanism; Fig. 2 is a side view 35 of the staff removed; Fig. 3 is a plan view of the part shown in Fig. 1. Fig. 4 is a perspective view of one of the protecting sleeves for the pivots of the balance wheel staff; Fig. 5 is a perspective view of the top jewel 40 holder; Fig. 6 is a plan view of the cap jewel holder spring.

Referring more particularly to the drawings, 1 denotes my improved balance wheel staff, the main portion of which may be of 45 the usual or any suitable construction. On the upper end of the staff is formed an upper pivot 2 the end of which is reduced as at 3 to engage the hole and cap jewels hereinafter described. On the inner end of the 50 pivot 2 is formed an annular groove 29 and an enlargement 4 which is beveled or inclined above and below to form an edge or sharp annular shoulder 5 the purpose of which will be hereinafter described. On 55 the opposite end of the staff is a pivot 6 at

the inner end of which is formed an annular groove 6^a and an enlargement 7 which is beveled above and below to form an edge or sharp annular shoulder 8. To the staff 1 is adapted to be secured in any suitable manner the usual or any suitable form of balance wheel (not shown.)

In the upper balance wheel supporting or face plate 9 is formed an annular bearing opening 10 the lower portion of which is reduced as at 11 to form an annular shoulder on the wall of said opening. Arranged in the aperture 10 is an upper pivot protecting sleeve 12 on the upper end of which is an annular flange 13 which engages the enlarged upper portion of the aperture 10 and thereby supports the sleeve in position. Engaged with the upper portion of the aperture 10 is a centering collar 14 having an annular flange 15 which projects over and 75 rests on the upper surface of the plate 9. Engaged with the flanged upper end of the sleeve 12 is an upper apertured jewel 16 through which the reduced outer end 3 of the pivot 2 passes. Resting on the jewel 16 80 is a cap jewel holder 17 in the lower side of which is a centrally disposed socket 18 in which is arranged the upper cap jewel 19, said jewel being of substantially semi-oval shape with its flat side lowermost and in 85 position to receive the reduced end 3 of the upper pivot, said end bearing against the jewel 19 as shown.

The cap jewel holder 17 is centered on the apertured jewel 16 and in the collar 14 by 90 an annular centering ring or holder 20. The cap jewel holder 17 and the cap jewel are yieldingly held in position to form a flush bearing for the upper end of the pivot 2 of the staff by an upper cap holding 95 spring 21 substantially V-shaped and secured at its apex to the upper side of the collar 14 by a screw 22 and the forked or diverging arms 23 project over and engage the outer face of the cap jewel holder as 100 shown. The spring 21 also spans and holds one side of the centering ring 20 in place, said ring being held in place at its opposite side by a screw 24 arranged in the upper side of the collar 14 as shown. Loosely 105 mounted on the flanged upper portion of the collar 14 is the balance spring adjusting lever 25 of the watch.

In the lower or bottom balance wheel supporting plate 26 is a jewel receiving aper-

ture 27 the lower end of which is reduced as at 28. Engaged with the aperture 27 and resting on the shoulder formed by the reduced lower end thereof is a lower hole jewel 29 through which the lower end of the pivot 6 projects and is revolvably held in position. Engaged with the reduced portion of the aperture 28 is a lower cap jewel holder 30 having therein a centrally disposed socket 31 in which is arranged a lower substantially semi-oval shaped lower cap jewel 32 the flat surface of which is uppermost and is adapted to receive the end of the lower pivot 6 which bears thereon as shown. The lower cap jewel holder 30 is held in position to yieldingly support the lower cap jewel 32 and lower end of the balance staff by a lower jewel holder supporting spring 33 which is constructed in the same manner as the upper jewel holder spring 21 and is secured to the lower plate 26 by a screw 34 as shown.

Engaged with the upper portion of the aperture 27 in the plate 26 is a lower pivot protecting sleeve 35 having on its lower end an annular radially projecting flange 36 which fits in the upper portion of the aperture 27 and rests on the upper side of the hole jewel 29. The sleeve 35 is held in place in the aperture 27 by screws 37 arranged in the plate 26 and having their heads engaged with the edges of the flange 36 of the sleeve as shown. Arranged in the upper plate 9 is a balance spring post 38 to which is adapted to be secured in the usual manner the usual balance spring (not shown).

By yieldingly holding the upper and lower jewels of the staff in position as herein shown and described it will be seen that the staff will be permitted to give or yield longitudinally when affected in this direction by the jarring or shaking of the watch, the yielding support for the jewels taking up the shocks and jars occasioned by shaking or bringing the watch into forcible engagement with other objects and which would otherwise be applied to the balance wheel with more or less disastrous results. By providing the protecting sleeves 12 and 35 for the upper and lower pivots of the balance staff and providing said staves with the annular enlargements it will be seen that the staff will be held against lateral movement in any direction which might result in breaking the ends of the pivots or the jewels with which they are engaged. By forming sharp annular shoulders on the enlargements of the pivots the friction occasioned by the engagement of these enlargements with the inner surfaces of the protecting sleeves is reduced to a minimum.

From the foregoing description taken in connection with the accompanying drawings, the construction and operation of the

invention will be readily understood without requiring a more extended explanation.

Various changes in the form, proportion and the minor details of construction may be resorted to without departing from the principle or sacrificing any of the advantages of the invention as claimed.

Having thus described my invention, what I claim is;

1. In combination, a face plate provided with an opening having the wall thereof provided with an annular shoulder, a bottom plate having an opening, a staff having an annular groove at a point removed from each end thereof and that portion outwardly with respect to the groove tapering and merging in a reduced terminus to provide a pivot, a flanged protecting sleeve mounted against said shoulder and projecting from said face plate and extending into the groove at the upper end of the staff, a flanged protecting sleeve seated in and projecting from the bottom plate and extending into the groove at the lower end of the staff, a pair of jewels abutting against the flanged end of each sleeve, one of said jewels being provided with an opening for the passage of a pivot and the other of said jewels having a socket for the reception of the pivot, said sleeves coöoperating with said plates for maintaining the staff in position.

2. A balance wheel staff for watches having its ends reduced to form pivots, upper and lower balance wheel supporting plates having apertures therein, upper and lower hole jewels arranged in said apertures and adapted to receive the ends of said pivots, cap jewel holders engaged with said hole jewels, cap jewels arranged in said holders and adapted to form thrust bearings for the ends of the pivots, an upper centering collar arranged in the aperture of said upper support, an upper holder centering ring arranged in said collar, and a jewel holder spring secured at one end to said centering collar and at its other end to said upper cap jewel holder, said spring spanning said centering ring and adapted to engage and yieldingly support the cap jewel holders in place.

3. A balance staff for watches having its ends reduced to form pivots, annular enlargements formed on the inner ends of said pivots, said enlargements being beveled above and below to form sharp annular shoulders, balance wheel supporting plates having apertures therein, jewels yieldingly secured in said apertures to receive said pivots, whereby the staff is yieldingly and revolvably supported, pivot protecting sleeves having flanged outer ends engaged with and secured in the apertures of said plates, whereby said sleeves are supported in position to encircle said annular shoulders and

to hold the pivots of the staff against lateral movement in any direction forming a bearing with which the sharp annular shoulders on the enlargements of the pivots 5 are engaged when the balance wheel shaft is jarred in a lateral direction.

4. A balance wheel staff for watches having its ends reduced to form pivots, balance wheel supporting plates having apertures 10 therein, hole jewels arranged in said apertures and adapted to receive the ends of said pivots, cap jewel holders engaged with said hole jewels, cap jewels arranged in said holders and adapted to form thrust 5 bearings for the ends of the pivots, a jewel

centering collar arranged in the aperture of 20 one of said supports, a centering ring arranged in said collar, a V-shaped jewel holder spring secured at one end to said centering collar and having its arms engaged with said cap jewel holder, whereby the latter 25 and the pivot supporting jewels are yieldingly held in position.

In testimony whereof I have hereunto set my hand in presence of two subscribing witnesses.

TEOFIL SOKOLOWSKI.
